(57) **CLAIM**

The ornamental design for a multi-axis machine, as shown and described.

DESCRIPTION

FIG. 1 is a front, left perspective view of a multi-axis machine, according to a first embodiment;

FIG. 2 is a back, right perspective view of the multi-axis machine shown in FIG. 1;

FIG. 3 is a top plan view of the multi-axis machine shown in FIG. 1;

FIG. 4 is a bottom plan view of the multi-axis machine shown in FIG. 1;

FIG. 5 is a front elevational view of the multi-axis machine shown in FIG. 1;

FIG. 6 is a back elevational view of the multi-axis machine shown in FIG. 1;

FIG. 7 is a right elevational side view of the multi-axis machine shown in FIG. 1;

FIG. 8 is a left elevational side view of the multi-axis machine shown in FIG. 1;

FIG. 9 is a front, left perspective view of a multi-axis machine, according to a second embodiment;

FIG. 10 is a back, right perspective view of the multi-axis machine shown in FIG. 9;

FIG. 11 is a top plan view of the multi-axis machine shown in FIG. 9;

FIG. 12 is a bottom plan view of the multi-axis machine shown in FIG. 12;

FIG. 13 is a front elevational view of the multi-axis machine shown in FIG. 9;

FIG. 14 is a back elevational view of the multi-axis machine shown in FIG. 9;

FIG. 15 is a right elevational side view of the multi-axis machine shown in FIG. 9; and,

FIG. 16 is a left elevational side view of the multi-axis machine shown in FIG. 9.

The features shown in broken lines do not form part of the claimed design.
